UNIVERSAL INSULATOR

Alfons Barnsteiner and Edwin H. Lockwood,
Mansfield, Ohio, assignors to Westinghouse
Electric & Manufacturing Company, East Pitts-
burgh, Pa., a corporation of Pennsylvania

Application November 29, 1939, Serial No. 306,686

3 Claims. (Cl. 174—162)

Our invention relates to insulators and more particularly to universal insulators for use with range structures, or the like.

Ceramic insulators slidably mounted upon suitable supporting fingers, rigidly attached to the rear wall of a range, have heretofore been used for supporting wires for use with electric ranges. These ceramic insulators have been of a well-known type, with elongated slots located within only two opposite surfaces to afford means of engaging the supporting structures. However, the use of such individual insulators mounted in pairs (as sometimes required) on a supporting structure greatly increases the manufacturing cost of the present day range, inasmuch as the use of two or more such insulators increases the time required to assemble such range as well as making such structure more difficult to assemble.

In contrast with separate insulators which must be individually mounted upon suitable supporting structures, we propose to use a single insulator capable of supporting two or more electrical wires and inherently capable of being mounted in either of two operating positions. This novel insulator enables a workman to more readily assemble the range structure and at the same time insures a positive, rugged structure.

It is, therefore, an object of our invention to provide a universal insulating member which may be slidably positioned upon a supporting structure in either of two operating positions.

A further object of our invention is to provide an inexpensive, rugged, compact block-shaped insulator having elongated slots formed within the sides and also the ends thereof, substantially parallel to the top and bottom surfaces for co-operating with a suitable supporting structure to rigidly attach such insulator to a range structure, or the like, in either of two significant positions.

Other objects of our invention will either be pointed out specifically in the course of the following description of a device embodying our invention, or will be apparent from such description.

In the accompanying drawing:

Figures 1 and 2 are partial, sectional and rear views, respectively, of a range illustrating insulating members embodying our invention associated therewith;

Figures 3, 4, and 5 are top, front, and side views, respectively, of the insulating member embodying our invention upon a supporting structure illustrating one of its operative positions;

Figures 6, 7, and 8 are top, front, and side views, respectively, of the insulating device embodying our invention mounted within a second supporting structure illustrating another operating position thereof; and

Figure 9 is a perspective view of the insulating member embodying our invention.

Referring to the accompanying drawing, in which like reference characters indicate like parts in the several figures, we show a universal insulator 10 removably associated with supports 12 and 14 which may be rigidly attached to the rear cover plate 16 and back splasher 18 of, say, a range structure 20 to support necessary electric wires 22 operatively associated with, say, a switch 24.

The insulating member 10 is a six sided member formed as a rectangular parallel piped with elongated cylindrical apertures 26 extending therethrough. The apertures 26 preferably extend transversely through the member from the top to the bottom surfaces thereof. Elongated slots 28 are formed within the sides and ends of the member 10 substantially parallel to the top and bottom surfaces thereof. The slots 28 are preferably located along the line substantially midway between such top and bottom surfaces and each slot is thus a continuation of the slots located at each end thereof so as to form substantially a continuous slot around the insulator. The slots 28 are formed within the structure or member 10, a distance suitable to afford satisfactory engagement with the supporting structures 12 and 14.

Vertically extending notches 30 may, if desired, be formed with in the four corners of the structure 10 so as to extend from the top to the bottom surfaces thereof. These notches 30 are located or formed within the structure 10 to afford cooperation with the supporting structures 12 and 14 so as to enable such structures to more rigidly attach the insulating member thereto, as hereinafter described.

The supporting structure 12 is, in this instance, formed from a single sheet of metal having upwardly extending fingers 32 and a lower supporting portion 34 substantially normal thereto. The fingers 32 are spaced apart such a distance as to permit the insulator 10 to be slid downwardly therebetween with such fingers being located within the elongated slots 28. The fingers 32 are slightly longer than the insulator 10 to enable the upper ends thereof to be bent backwardly and forwardly upon the insulator. Such bending of the upper portions of the fingers 32

cooperates with the upper edge of the insulator 10 preventing such insulator from being removed from the supporting structure 12 (see Figures 1 and 2.) The bent upper portions of fingers 32 are adapted to fit within the corner notches 33 and to be substantially flush with the top surface of the insulators.

The supporting structure 14 comprises a plurality of fingers 36 and a lower supporting portion 38 formed substantially normal to such fingers. Structure 14 is similar to the supporting structure 12. However, the distance between the fingers 36 is greater than the distance between the fingers 32 of structure 12. The distance between such fingers 36 is substantially equal to the length of the insulator 10 less twice the depth of the elongated slots 28 formed within the ends thereof. The structure 14 is thus adapted to receive and support the insulator 10 in a horizontal position or in a position with the longitudinal axis of the insulator 10 substantially parallel to the support portion 38 of the supporting structure 14. The upper ends of fingers 32 extend above the insulator 10 and may likewise be bent over upon the insulator 10 to prevent the removal of such insulator 10 therefrom, as hereinabove described.

When utilizing the supporting structures 12 and 14 with a range structure, the supporting portions 34 and 38, respectively, thereof are rigidly attached to the rear portion of the range structure. The fingers 32 and 36, respectively, of the structures 12 and 14 extend backwardly substantially normal to the rear surface of the range structure. This enables the insulating members or structures 10 to be mounted substantially normal to the rear surface of the range structure. The apertures 26 extending through the insulators 10 are thus positioned substantially parallel to the rear surface of the range. The necessary wires 22 of the range may then be positioned within the apertures 26 and thus be mounted or located substantially parallel to the rear surface of the range structure.

When wiring the range structure utilizing the insulators embodying our invention after the support brackets 12 and 14 have been rigidly attached thereto, such insulators are positioned within the supporting brackets 12 and 14. The insulators 10, being universal in operation, may be attached to either type of supporting bracket 12 or 14. In other words, the operator merely picks up any insulator and inserts it within the supporting fingers 32 or 36. The exact location of the insulator is thus predetermined by the type of bracket previously attached to the range structure at a predetermined position. In other words, the supporting members 12 and 14 retain the insulator upon the range structure in any predetermined position.

It is, therefore, obvious that an operator may thus attach insulators to the surface of the range structure or the like without paying any particular attention to the general location or arrangement desired, inasmuch as the supporting brackets to receive such insulators have been predeterminedly attached to such structure. The electric wires used on the range structure and operatively associated with the heating elements and switch 24 are thus inserted through the apertures 26 without any special regard to the relative position of such insulators.

Various modifications may be made in the

device embodying our invention without departing from the spirit and scope thereof, and we desire, therefore, that only such limitations shall be placed thereon as are imposed by the prior art and the appended claims.

We claim as our invention:

1. A universal insulator comprising a rectangular parallelepiped block of insulating material having a plurality of apertures extending through the block from top to bottom thereof for supporting conductors, said block having a pair of spaced apart longitudinally extending shoulders formed only on the opposite sides and ends thereof, said shoulders extending a sufficient distance along the block to thereby define pairs of parallel grooves on the ends and sides of said block whereby the block may be supported in one position between a pair of spaced supporting members engaged within one pair of grooves, or in another position between another pair of spaced supporting members engaged within the other pair of grooves, the adjacent ends of said shoulders defining a space to receive the ends of said supporting members when the ends are bent over into locking position.

2. The combination with U-shaped supporting members having different spacing between the arms of the members, of a universal insulator block having the shape of a rectangular parallelepiped, said block having means for supporting conductors, and having a pair of spaced apart longitudinally extending shoulders formed on opposite sides and ends thereof, said shoulders extending a sufficient distance along the block to thereby define pairs of parallel grooves on the ends and sides of said block, said grooves being adapted to slidably engage selectively the spaced arms of either of said supporting members whereby the block may be supported on one of said members with the cord supporting means in one position and on another of said members with the cord supporting means in another position, said shoulders also defining notches at the intersecting edges of the sides and ends of the block into which the ends of said supporting arms may be bent to thereby retain said insulator in position on the supporting member.

3. The combination with U-shaped supporting members having different spacing between the arms of the members, of a universal insulator block having the shape of a rectangular parallelepiped, said block having apertures extending therethrough from top to bottom for supporting conductors, and having a pair of spaced-apart longitudinally extending shoulders formed only on opposite sides and ends thereof, said shoulders extending a sufficient distance along the block to thereby define pairs of parallel grooves on the ends and sides of said block, said grooves being adapted to slidably engage selectively the spaced arms of either of said supporting members whereby the block may be supported on one of said members with the apertures in one position and on another of said members with the apertures in another position, said shoulders also defining notches at the intersecting edges of the sides and ends of the block, into which the ends of said supporting arms may be bent to thereby retain said insulator in position on the supporting member.
